CLAIM

The ornamental design for a table lamp, as shown and described.

DESCRIPTION

FIG. 1 is a front perspective view of a table lamp, showing my new design;

FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof; and,
FIG. 9 is an enlarged view of section 9 of FIG. 1.
The evenly-spaced broken lines in the drawings illustrate the portions of the table lamp, which form no part of the claimed design. In FIGS. 1 and 9, the dash-dot-dash broken lines represent a sectional designation that forms no part thereof.
